UNITED STATES PATENT OFFICE.

ALEXANDER KWIATKOWSKI, OF MIDDLETOWN, CONNECTICUT.

FIRE-ESCAPE.

1,113,651.

Specification of Letters Patent.

Patented Oct. 13, 1914.

Application filed May 19, 1914. Serial No. 839,528.

To all whom it may concern:

Be it known that I, ALEXANDER KWIATKOWSKI, a subject of the Czar of Russia, residing at Middletown, in the county of Middlesex and State of Connecticut, have invented certain new and useful Improvements in Fire-Escapes, of which the following is a specification.

This invention relates to certain new and useful improvements in fire escapes.

An object of the invention is to provide a fire escape of the portable type which may be mounted upon a vehicle and moved to the desired location for use.

15 A further object of the invention is to provide a portable fire escape consisting of a plurality of telescoping tubes with manually-controlled operating means to cause the same to be distended, with the outer end of 20 the outer tube suitably positioned as desired.

With the above general objects in view and others that will appear as the nature of the invention is better understood, the same consists in the novel construction, combination 25 and arrangement of parts to be herein-after more fully described and then claimed.

In the accompanying drawings in which is shown the preferred embodiment of my invention and to which reference is had 30 herein by like characters denoting corresponding parts throughout the several views:—Figure 1 is a side elevational view of the device. Fig. 2 is a top plan view of the same. Fig. 3 is a side elevational view 35 of the device with the telescoping tubes partially elevated and distended, with a motor shown in dotted lines for distending the tubes. Fig. 4 is a view taken on line IV—IV of Fig. 1. Fig. 5 is a top plan view 40 partly in section of a portion of the telescoping tubes, illustrating the manner of distending the same. Fig. 6 is a detail sectional view of the lower end of the tube illustrating the cushioning means with the 45 exit opening. Fig. 7 is a cross-sectional view taken on line VII—VII of Fig. 5, and, Fig. 8 is a detail view of the rope connection with the tubes.

Referring more in detail to the drawings, 50 the reference numeral 10 designates in general the vehicle for supporting a plurality of telescoping tubes and comprises more specifically a pair of side bars 11 connected at their rear ends to the bracket 12 and at 55 their forward ends to the bracket 13, the bracket 13 being suitably supported on the

fifth wheel 14 at the front end of the vehicle. Pivotally-connected as at 15 to the upright arms of the rear bracket 12 is a substantially U-shaped frame 16 closed at its outer end as at 17 and provided with an opening in the end 17 in which is mounted a sheave 18. The frame 16 is provided adjacent its outer end in one of the side rails thereof with an opening 19, for purposes to be later described, while the same rail has mounted in the bracket arm 20 carried adjacent the inner end thereof, a reel 21, the shaft of the reel being provided with a suitable pawl and ratchet mechanism 22 and operating handle 23.

There is provided a plurality of telescoping tube sections 24 which constitute the means of escape or passage for persons making their exit from a burning building, the outlet for the telescoping tubes being in the lower tube and indicated at 25. These outlets 25 are lateral openings in the inner tube, suitable platforms 26 being carried by the lower tube and positioned adjacent the exit 80 openings 25. Means are provided at the lower end of the inner tube in the form of a cushion to resist the force of a person descending in the tube and consists of the coil spring 27 of a diameter substantially equal 85 to the inner diameter of the tube 24 and covered by the plate 28. The lower tube is pivotally-connected as at 29 to the upright arms of the front bracket 13 while the other end of the tube sections is supported upon 90 the rear bracket 12 as clearly illustrated in Fig. 1. Each of the tube sections 24 is provided at the outer end thereof with a collar 30, each of said collars carrying oppositely-disposed bracket arms 31 for the support of sheaves 32 as clearly illustrated in 95 Figs. 5 ad 7.

The lower tube section 24 carries a bracket arm 33, of a shape to snugly engage the periphery of the said tube section and has journaled in the lower ends thereof a shaft 34 for supporting a plurality of reels 35 and 36, arranged in spaced relation on the shaft 34. The reels 35 are spaced outwardly of the bracket 33 as clearly illustrated in Figs. 3 100 and 4 while the reel 36 is positioned on the shaft 34 intermediate of the bracket arms 33. Pawl and ratchet mechanism 37 is mounted upon the shaft 34 and holds the same in adjusted position, the shaft being operated by 105 the crank handle 38. Ropes or cables 39 are connected at one end to the inner ends of the

tube sections 24, as illustrated in Fig. 8, there being provided screws 40 carried by the inner ends of each tube to which are secured the ends of the ropes, the ropes 39 passing through grooves 41 formed in the sides of the tube sections 24, as clearly shown in Figs. 5 and 7, these ropes 39 passing over the sheaves 32 and connected at the point 42 to the rope 39 of the adjacent tube section. 5 These ropes or cables 39 are provided at each side of the tube sections 24 and passing over the sheaves 32 as clearly shown, with the lower rope sections 39 wound upon the rails 35. A second rope or cable 42' is connected 10 to the outer end of the outer tube section 24 as at 43 and has its other end wound upon the reel 36 in a direction opposite to the winding of the cables 39 upon the reels 35. A cable 44 is connected at one of its ends as 15 at 45 to the outer end of the inner tube section and passes over the sheave 18 through the opening 19 in the side rail 16 of the frame and wound at its other end upon the reel 21. 20 25 The operation of the device is as follows:—Any suitable propelling means may be provided for the carriage 10; the same may be in the form of an automobile or may be drawn by horses and when moved to the 30 location for use, the rope 44 is wound upon the reel 21 which will cause the tube sections 24 to be elevated at their forward ends as shown in Fig. 3, with the entrance platform 46 to the outermost tube section 24 positioned adjacent the point of exit of a building. The tube sections are held in elevated 35 position by the pawl and ratchet mechanism 22 before described. Should it be desired to extend the tube sections to increase the 40 length of the chute, the reels 35 are operated by the crank handle 38 to wind thereon the cables 39. It is to be noted that the first telescoping tube section 24 is moved outwardly as shown in Fig. 3 until the slack in 45 the cable 39 is taken up and wound upon the reel 35, after which the second cable 39 will begin to remove the next tube section 24 from its telescoping section, and in a like manner be distended until the slack in the 50 operating cable therefor is taken up. Each

of the adjacent tube sections is moved outwardly with a successive movement, that is, when the slack in the operating cables 39 is taken up, its tube section begins its outward movement. When it is desired to retract 55 the tube sections or cause the same to telescope to a closed position as shown in Figs. 1 and 2, the pawl and ratchet mechanism 37 is released and the crank 38 operated in a reverse direction to wind thereon the cable 60 42' connected to the outermost tube section which will cause the tube section to telescope. A person entering the tube sections from the platform 46 will have a gradual descent therein, while the velocity of descending movement is diminished by engagement with the cover 28 for the cushioning spring 27, there of course being attendants at the lowermost tube adjacent the openings 25 to assist the exit of the occupants. As 70 shown in Fig. 3, a motor 47 may be utilized as a power means for distending the tube sections in lieu of the hand crank 38.

While I have herein shown and described the preferred embodiment of my invention, 75 I do not wish to confine myself to the exact details of construction as shown, as various forms, modifications and arrangement of the parts may be had without departing from the spirit and scope of the invention as 80 claimed.

What I claim as new is:—

In a fire escape, a plurality of telescoping tubes carried by a vehicle, the opposite side of each tube being longitudinally grooved, 85 a rope connected to the inner end of each tube and lying within said groove, each rope being connected at its other end to the adjacent rope, a reel supported on the lower tube, and having the rope connected to the 90 adjacent tube wound thereon, and a rope connected to the outer end of the outer tube wound upon the reel at its other end.

In testimony whereof I affix my signature in presence of two witnesses.

ALEXANDER KWIATKOWSKI.
